PROCESS OF MANUFACTURING MOTOR FUEL

Frederick E. Frey, Bartlesville, Okla., assignor to
Phillips Petroleum Company, a corporation of
Delaware

Application April 2, 1940, Serial No. 327,529

14 Claims. (Cl. 196—10)

The invention relates to a process of manufacturing motor fuel, and more particularly to the manufacture of motor fuel of increased anti-knock rating and decreased volatility from aliphatic hydrocarbons having three to ten carbon atoms to the molecule.

The invention comprises, in combination, the following steps: alkyllating isoparaffins of relatively low molecular weight, such as isobutane, isopentane, and isohexanes, with olefins to yield chiefly isoparaffins that have a relatively low volatility and that boil in the motor-fuel range; subjecting the resultant motor-fuel hydrocarbons and the accompanying hydrocarbons of relatively lower molecular weight to dehydrogenating conditions, which cause a conversion of part of the motor-fuel hydrocarbons to hydrocarbons of substantially the same boiling range but of substantially greater anti-knock rating and a conversion of part of the paraffins of relatively lower molecular weight to the corresponding olefins; separating from the resultant mixture the hydrocarbons boiling in the motor-fuel range; and returning at least a part of the residual hydrocarbons of relatively lower molecular weight to the alkylation step.

An object of this invention is to provide a process of manufacturing motor fuel.

Another object is to utilize aliphatic hydrocarbons having from three to five carbon atoms per molecule for the manufacture of motor fuel.

Another object is to reduce the volatility of the lower isoparaffins, having from four to six carbon atoms to the molecule, and thus to improve them for incorporation in motor fuel.

Another object is to increase the anti-knock rating of motor fuel produced by the alkylation of isoparaffins with olefins.

Another object is to effect, in one conversion step, an increase in the anti-knock rating of motor fuel produced by the alkylation of isoparaffins with olefins and a dehydrogenation of paraffins of low molecular weight to olefins suitable for the production of additional amounts of motor fuel by alkylation.

Other objects and advantages of this invention will be obvious to those skilled in the art from the following disclosure and discussion.

The invention will be readily understood from the following description and the accompanying drawing, which shows a flow-diagram for a preferred mode of operation.

The feed, comprising isoparaffins of relatively low molecular weight, such as isobutane, isopentane, and isohexanes, enters the system 55

through inlet 1 having control-valve 2. The isoparaffins are subjected to alkylation in the alkylator 3; the olefins required for the alkylation are introduced into the alkylator either with the feed or otherwise as by one or more auxiliary inlets (not shown) that facilitate maintaining an olefin concentration that is low compared to the concentration of isoparaffins in the alkylator. By the alkylation originally charged isoparaffins are converted into heavier isoparaffins that boil principally in the motor-fuel range, such as isooctanes, isooctanes, isononanes, isodecane, and the like.

From the alkylator the effluent, containing newly formed isoparaffins and unreacted hydrocarbons, passes through conduit 4 and valve 5 to the heater 6, where the hydrocarbons are heated to a temperature within the dehydrogenating range, generally between 750 and 1250° F.

20 Thence the hydrocarbons are maintained under dehydrogenating conditions in the dehydrogenator 7 until a desired degree of dehydrogenation has been effected, advantageously in the presence of a dehydrogenating catalyst such as catalysts comprising alumina, bauxite, especially hard Arkansas bauxite, chromium oxide, especially black unglowed chromium oxide, or the like. The temperature preferably is between 750 and 1100° F. when the dehydrogenation catalyst comprises black unglowed chromium oxide, and between 1000 and 1250° F. when the catalyst consists of alumina or bauxite, or the like.

Alternatively, valve 5 being closed, the hydrocarbons from the alkylator 3 may be passed through conduit 8 and valve 9 into the fractionator 10, wherein a fractionation into a light and a heavy fraction is made. The light fraction which contains the major part of the hydrocarbons boiling in the motor-fuel range and all of the lighter hydrocarbons, passes through conduit 11 and valve 12 to the heater 6 and dehydrogenator 7, where, as has been explained, a desired degree of dehydrogenation is effected.

40 The heavy fraction from the fractionator 10 may be withdrawn, under certain conditions of fractionation, as an oil through valve 13 and outlet 14; or, alternatively, under such conditions of fractionation that it contains a considerable but minor part of the hydrocarbons boiling in the motor-fuel range, it may be passed through valve 15 and conduit 16 to the separating means 17; or, still alternatively, if the conditions of operation are such that the heavy fraction from fractionator 10 consists predominantly of heavy unsaturated hydrocarbons such

50

as polymers of the gaseous olefins that boil above the motor-fuel range, part or all of it may be passed through valve 18 into the recycle stream 19, which carries the heavy unsaturated hydrocarbons to the alkylator 3, where they may be used to alkylate isoparaffins. Such heavy unsaturated hydrocarbons, especially heavy polymers and/or co-polymers of propylene and the several butylenes, appear to be practically as suitable for the alkylation of isoparaffins as the gaseous olefins themselves, inasmuch as certain heavy olefin hydrocarbons undergo fragmentation in the reaction, thereby giving rise to the production of an alkylation product of equal or greater volatility by union of the fragments with simple isoparaffins.

From the dehydrogenator 1, the mixture comprising dehydrogenated hydrocarbons and unreacted hydrocarbons passes through conduit 20 into the separating means 17, wherein this mixture, and any heavy fraction brought from fractionator 10 by conduit 16, are separated into a light-gas fraction containing hydrogen and the major part of any hydrocarbons having less than three carbon atoms to the molecule, a heavy-gas fraction containing mainly hydrocarbons boiling below the desired motor-fuel range, a motor-fuel fraction, and a heavy-oil fraction.

The light-gas fraction is withdrawn from separating means 17 through valve 21 and outlet 22. The motor-fuel fraction is withdrawn through valve 23 and outlet 24. The heavy-oil fraction may be withdrawn through valve 25 and outlet 26; or alternatively, part or all of the heavy-oil fraction may be passed, especially if it consists predominantly of heavy polymers of propylene and/or the several butylenes, through valve 27 into the recycle stream 19, which carries the heavy polymers to the alkylator 3.

The heavy-gas fraction from separator 17 may be passed through conduit 28 and valve 29 into the recycle stream 19, which carries the heavy gases to the alkylator 3. Alternatively, valve 29 being closed, the heavy-gas fraction from separating means 17 may be passed through valve 30 and conduit 31 to the heater 32, wherein the heavy-gas hydrocarbons are heated to a temperature within the dehydrogenating range, generally between 750 and 1250° F., and thence into the dehydrogenator 33, wherein the hydrocarbons are maintained under dehydrogenating conditions similar to those already described for dehydrogenator 1 until the content of olefin hydrocarbons has been increased to a desired value; or, still alternatively, valves 29 and 30 being closed, the heavy-gas fraction from separating means 17 may be passed through valve 34 and conduit 35 into the separator 36, wherein the paraffins are separated from the olefins, as by solvent extraction, azeotropic distillation in the presence of a polar oxygen-containing compound such as sulfur dioxide, ethylene oxide and methyl formate, and the like, as described in the Patent 2,186,524, of Frey et al. The paraffins pass from the separator 36 through valve 37 and conduits 38 and 39 to the heater 32 and dehydrogenator 33, where they undergo dehydrogenation to a desired extent. The olefins pass from the separator 36 through valve 39 and conduit 40 into the recycle stream 19, which carries them to the alkylator 3.

From the dehydrogenator 33, the products of dehydrogenation and the unreacted paraffins may be passed through valve 41 and conduit 42 into recycle stream 19, which carries them to the alkylator 3; or, alternatively and preferably, valve

41 being closed, the dehydrogenation products and the unreacted paraffins may be passed through valve 43 and conduit 44 into separating means 45, wherein separation into a light-gas fraction and a heavy-gas fraction is effected. The light-gas fraction, consisting mainly of hydrogen and the major part of any hydrocarbons having less than three carbon atoms per molecule, is withdrawn through valve 46 and outlet 47. The heavy-gas fraction, consisting mainly of olefins and paraffins having at least three carbon atoms per molecule, passes through valve 48 into the recycle stream 19, which carries it to the alkylator 3; however, if desired, part or all of the heavy-gas fraction may be passed through valve 49 and conduit 50 into separator 36, wherein separation into olefins, which pass through valve 39 and conduits 40 and 19 to the alkylator 3, and into paraffins, which pass through valve 37 and conduit 38 to the heater 32 and thence into dehydrogenator 33, is effected. The best mode of procedure for any given feed stock may be readily determined by trial. Olefins suitable for reaction in alkylator 3 may, if desired, be introduced through conduit 51 and valve 52 to conduit 19, either as the sole olefin charge to the alkylator 3 or to supplement olefins formed in the process.

It will be readily appreciated that the diagram serves only as a flow sheet which shows the essential functional elements which contribute to the combination of the process. In actual operation there are included numerous pumps, compressors, cooling and heating units, etc., all of which are incidental to the major units shown and can be readily supplied and adapted in known modifications by one skilled in the art. Separating means 17 and 45 generally comprise various compressors, fractionators and the like, and separator 36 generally operates with the agency of a selective solvent, many of which are known to the art and all of which require various pieces of equipment not shown.

Feed stocks suitable for the process may include mixtures of paraffin hydrocarbons of from three to ten carbon atoms per molecule, provided that a substantial proportion of isoparaffins is present. Suitable mixtures are natural gasoline, casinghead gasoline, crude oil distillates, and other similar mixtures comprising isoparaffins having from four to six carbon atoms per molecule. These isoparaffins, namely, isobutane, isopentane, and isohexanes, are the chief components of such mixtures for which a reduction of volatility by alkylation is desirable. The normal paraffins present in such mixtures also may undergo alkylation, although generally only to a relatively minor extent, depending upon conditions present during the alkylation step. Of the paraffins that do not undergo alkylation, part of the relatively heavy ones, especially of the heavy normal paraffins, pass through the process unchanged and are incorporated as such in the motor-fuel product; part of the relatively heavy ones are converted in the dehydrogenation step into olefins, aromatics, and cycloolefins that boil in the motor-fuel range and that are incorporated in the motor-fuel product; part of the relatively light ones undergo conversion in the same and/or a subsequent dehydrogenation step into olefins that serve as reactants for the alkylation of isoparaffins; and a relatively minor part of the relatively light ones break up into very light hydrocarbons that advantageously are vented from the system with the hydrogen obtained as a by-

product from the dehydrogenation step or steps.

The alkylation step may comprise a thermal alkylation process such as that disclosed in the patent Frey, U. S. 2,002,394, and Frey 2,104,296 or a catalytic alkylation process using aluminum chloride, complex metal halides such as sodium chloroaluminate, zinc halides, concentrated sulfuric acid, concentrated hydrofluoric acid as disclosed in my copending applications Serial Number 315,063 filed January 22, 1940 and Serial Number 323,443, filed March 11, 1940, or other catalysts, as for example the process disclosed in the copending application of Frey et al., Serial No. 87,790 (Patent No. 2,233,363). However, either concentrated sulfuric acid or concentrated hydrofluoric acid is preferred as alkylation catalysts, as they have an advantageous ability to cause fragmentation of heavy polymers or other heavy unsaturated hydrocarbons into fragments, which unite with isoparaffins to give alkylation products which have higher molecular weights than the original isoparaffins, but which do not equal the molecular weights of the original isoparaffins and heavy olefins.

The following example is given to illustrate one of the many possible modes of operation; it is not necessarily to be taken as establishing limitations of the invention.

Example

This example illustrates a mode of operation suitable for the manufacture of a motor fuel from a petroleum cut, containing paraffins of three to ten carbon atoms per molecule, of which 85 per cent of the material having five or more carbon atoms per molecule distills up to 212° F. Such a petroleum cut may be subjected to alkylation with olefins, preferably of three to five carbon atoms per molecule, as in the presence of sulfuric acid having a strength of more than about 90 per cent, advantageously from 96 to 102 per cent. To minimize concurrent polymerization reactions, the mixture of hydrocarbons and sulfuric acid must be vigorously agitated, and the concentration of olefins must be kept low relative to the concentration of isoparaffins. The reaction temperature must be kept between 0 and 125° F., preferably at about 50 to 85° F. After a suitable extent of alkylation has been obtained, the hydrocarbons are freed from the acid. The hydrocarbons then are virtually olefin-free and have an increased amount of material having five or more carbon atoms to the molecule; of this material, only 60 to 65 per cent boils up to 212° F. After being freed from the alkylation catalyst, the hydrocarbons may be passed through a catalytic dehydrogenator containing bauxite, advantageously granular hard Arkansas bauxite washed free from dust particles in accordance with the copending application of Blaker and Matuszak, Serial No. 328,594, filed April 8, 1940, at a temperature of about 1000° F. or higher. The dehydrogenation and other reactions promoted by the bauxite effect a change in the octane number of the material having five or more carbon atoms to the molecule from an initial value of about 70 to a value of about 74. Accompanying this change in octane number there is an increase in the degree of unsaturation, but there is relatively little change in boiling characteristics. The hydrocarbons having three to five carbon atoms are likewise dehydrogenated to the corresponding olefins and may be returned to the alkylation step, either directly or after additional dehydrogenation in a second catalytic dehydrogenator.

Fractionation, removal of light gas, removal of heavy oil, separation of olefins from paraffins, recycling of heavy polymers to the alkylator, and the like steps may be practiced in accordance with 5 the more general description already given.

As is illustrated by the foregoing example, the invention effects the manufacture of motor fuel of increased anti-knock rating and decreased volatility from aliphatic hydrocarbons having 10 three to ten carbon atoms to the molecule. Aliphatic hydrocarbons having three to five carbon atoms to the molecule are utilized, and the volatility of isoparaffins having four to six carbon atoms to the molecule is reduced. An increase 15 in the anti-knock rating of motor fuel produced by alkylation of isoparaffins with olefins and a dehydrogenation of paraffins of relatively low molecular weight into olefins are effected in one conversion step.

20 As many modifications of the invention will be obvious to those skilled in the art, the invention should not be limited unduly by the foregoing specification and example, but it should be understood to be extensive in scope and equivalents, 25 within the scope of the appended claims.

I claim:

1. An improved process for the production of a motor fuel having a low volatility and a high 30 octane number, which comprises reacting by alkylation paraffin hydrocarbons of from three to six carbon atoms per molecule with olefin hydrocarbons to form paraffin hydrocarbons of a higher number of carbon atoms per molecule than said initial paraffins and in the motor fuel 35 boiling range, passing at least a part of the effluent of said first step comprising hydrocarbons in and below the motor fuel boiling range to the action of a dehydrogenation catalyst at a dehydrogenation temperature to improve the octane 40 number of motor fuel hydrocarbons and concomitantly to produce olefins lower boiling than motor fuel, separating from the dehydrogenation effluent a fraction comprising hydrocarbons in the motor fuel range and removing said fraction 45 from the process, separating also a fraction containing olefins lower boiling than motor fuel and passing said fraction to said alkylation step.

2. A process of manufacturing motor fuel, which comprises alkylating isoparaffins of four to 50 six carbon atoms to the molecule with olefins in the presence of concentrated sulfuric acid, subjecting the resultant motor-fuel hydrocarbons and the accompanying hydrocarbons of relatively lower molecular weight to the action 55 of a dehydrogenation catalyst at a dehydrogenation temperature, separating from the resultant mixture of the hydrocarbons boiling in the motor-fuel range, and returning at least a part of the residual hydrocarbons to the alkylation step.

3. A process of manufacturing motor fuel of increased anti-knock rating and decreased volatility from aliphatic hydrocarbons of from three to ten carbon atoms to the molecule and containing isoparaffins of four to six carbon atoms to the molecule, which comprises subjecting the 65 said hydrocarbons, together with recycled olefins, to the action of sulfuric acid having a strength of 90 to 102 per cent by weight, at a temperature between about 0 and 125° F. until a desired extent of alkylation is obtained; subjecting at least a part of the effluent of the alkylation operation comprising hydrocarbons in and below the motor fuel boiling range to the action of a solid dehydrogenation catalyst at a 70 temperature between 750 and 1250° F. for a peri-

od of time to obtain a substantial extent of dehydrogenation, separating from the resultant mixture the hydrocarbons boiling in the motor-fuel range; and returning at least a part of the residual hydrocarbons having from three to five carbon atoms to the molecule and containing said olefins to the alkylation step.

4. The process of claim 3 wherein the dehydrogenation catalyst comprises bauxite and the temperature is within the range of 1000 to 1250° F.

5. The process of claim 3 wherein the dehydrogenation catalyst comprises black unglowed chromium oxide and the temperature is within the range of 750 to 1100° F.

6. A process of manufacturing motor fuel of increased anti-knock rating and decreased volatility from aliphatic hydrocarbons of from three to ten carbon atoms to the molecule and containing isoparaffins of four to six carbon atoms to the molecule, which comprises subjecting the said hydrocarbons, together with recycled olefins, to the action of sulfuric acid having a strength of 90 to 102 per cent by weight, at a temperature between about 0 and 125° F. until a desired extent of alkylation is obtained; subjecting at least a part of the effluent of the alkylation operation comprising hydrocarbons in and below the motor fuel boiling range to the action of a solid dehydrogenation catalyst at a temperature between 750 and 1250° F. for a period of time to obtain a substantial extent of dehydrogenation, separating from the resultant mixture the hydrocarbons boiling in the motor-fuel range; subjecting at least a part of the residual hydrocarbons having three to five carbon atoms to the molecule to a second dehydrogenation step; and returning olefin hydrocarbons having three to five carbon atoms to the molecule from the second dehydrogenation step to the alkylation step as the recycle olefins.

7. A process of manufacturing motor fuel of increased anti-knock rating and decreased volatility from aliphatic hydrocarbons of from three to ten carbon atoms to the molecule and containing isoparaffins of four to six carbon atoms to the molecule, which comprises subjecting the said hydrocarbons, together with recycled olefins, to the action of sulfuric acid having a strength of 90 to 102 per cent by weight, at a temperature between about 0 and 125° F. until a desired extent of alkylation is obtained; subjecting at least a part of the effluent of the alkylation operation comprising hydrocarbons in and below the motor fuel boiling range to the action of a solid dehydrogenation catalyst at a temperature between 750 and 1250° F. for a period of time to obtain a substantial extent of dehydrogenation, separating from the resultant mixture the hydrocarbons boiling in the motor-fuel range; separating the residual hydrocarbons having three to five carbon atoms to the molecule into an olefin part and a paraffin part; returning the olefin part to the alkylation step as the recycle olefins; subjecting the paraffin part to a second dehydrogenation step; and returning the hydrocarbons having three to five carbon atoms to the molecule from the second dehydrogenation step to the alkylation step.

8. A process of manufacturing motor fuel of increased anti-knock rating and decreased volatility from aliphatic hydrocarbons of from three to ten carbon atoms to the molecule and containing isoparaffins of four to six carbon atoms to the molecule, which comprises subjecting the said

hydrocarbons, together with recycled olefins, to the action of sulfuric acid having a strength of 90 to 102 per cent by weight, at a temperature between about 0 and 125° F. until a desired extent of alkylation is obtained; passing the effluent to separating means, separating therefrom unsaturated hydrocarbons produced in side reactions by the action of said sulfuric acid and boiling above the motor-fuel range and returning same to the alkylation step; separating also a hydrocarbon fraction comprising motor-fuel hydrocarbons and hydrocarbons boiling below the motor-fuel range and subjecting same to the action of a dehydrogenation catalyst at a temperature in the range 750 to 1250° F. until a substantial extent of dehydrogenation is obtained; separating from the resultant mixture the hydrocarbons boiling in the motor-fuel range; and separating also from the resultant mixture at least a part of the residual hydrocarbons having from three to five carbon atoms to the molecule and returning same to the alkylation step, said unsaturated hydrocarbons and said residual hydrocarbons comprising said recycle olefins.

9. The process of claim 8 in which the dehydrogenation catalyst comprises black unglowed chromium oxide and the dehydrogenation temperature is in the range of 750 to 1100° F.

10. The process of claim 8 in which the dehydrogenation catalyst consists of bauxite and the dehydrogenation temperature is in the range of 1000 to 1250° F.

11. A process of manufacturing a motor fuel of increased anti-knock rating and decreased volatility from light petroleum distillates containing substantial amounts of isoparaffins of from four to six carbon atoms per molecule, which comprises subjecting such a distillate together with olefins to an alkylation reaction in which some of the paraffin hydrocarbons in said distillate react with said olefin hydrocarbons to produce paraffin hydrocarbons of higher molecular weight, passing at least a part of the effluent of said alkylation reaction comprising hydrocarbons boiling in and below the motor fuel range to the action of a dehydrogenation catalyst at a dehydrogenation temperature to improve the octane number of said hydrocarbons boiling in the motor fuel range and concomitantly to produce olefins lower boiling than motor fuel, separating from the dehydrogenation effluent a fraction comprising hydrocarbons boiling in the motor fuel range and removing said fraction from the process, separating also a fraction containing olefins lower boiling than motor fuel and passing said fraction to the alkylation operation.

12. A process of manufacturing a motor fuel of increased anti-knock rating and decreased volatility from natural gasoline containing substantial amounts of isoparaffins of from four to six carbon atoms per molecule, which comprises subjecting said natural gasoline together with olefins to an alkylation reaction in which some of the paraffin hydrocarbons in said natural gasoline react with said olefin hydrocarbons to produce paraffin hydrocarbons of higher molecular weight, passing at least a part of the effluent of said alkylation reaction comprising hydrocarbons boiling in and below the motor fuel range to the action of a dehydrogenation catalyst at a dehydrogenation temperature to improve the octane number of said hydrocarbons boiling in the motor fuel range and concomitantly to produce olefins lower boiling than motor fuel, separating from the dehydrogenation effluent a fraction

comprising hydrocarbons boiling in the motor fuel range and removing said fraction from the process, separating also a fraction containing olefins lower boiling than motor fuel and passing said fraction to the alkylation operation.

13. A process of manufacturing motor fuel, which comprises alkylating isoparaffins of four to six carbon atoms to the molecule with olefins in the presence of concentrated hydrofluoric acid, subjecting the resultant motor-fuel hydrocarbons and the accompanying hydrocarbons of relatively lower molecular weight to the action of a dehydrogenation catalyst at a dehydrogenation temperature, separating from the resultant mixture the hydrocarbons boiling in the motor-fuel range, and returning at least a part of the residual hydrocarbons to the alkylation step.

14. A process of manufacturing motor fuel of increased antiknock rating and decreased volatility from low boiling aliphatic hydrocarbons, which comprises subjecting paraffin hydrocarbons of from three to ten carbon atoms per mole-

5 cule together with recycled low boiling olefins to an alkylation reaction in which some of the paraffin hydrocarbons react with said olefin hydrocarbons to produce paraffin hydrocarbons of higher molecular weight and in the motor fuel boiling range, subjecting at least a part of the effluent of said alkylation-operation comprising hydrocarbons boiling in and below the motor fuel range to a catalytic treatment at an elevated 10 temperature such as to improve the antiknock rating of said hydrocarbons boiling in the motor fuel range, separating from the resultant mixture hydrocarbons boiling in the motor fuel range, subjecting at least a part of the residual 15 hydrocarbons having three to five carbon atoms per molecule to a second catalytic treatment at an elevated temperature such as to dehydrogenate paraffins and produce low boiling olefins, and returning olefin hydrocarbons having three to 20 five carbon atoms to the molecule so produced to the alkylation step as said recycled olefins.

FREDERICK E. FREY.
